UNITED STATES PATENT OFFICE.

WALTER D. STAFFORD, OF PITTSFIELD, MASSACHUSETTS.

ATTACHMENT FOR VIOLIN-CASES.

1,201,523.

Specification of Letters Patent. Patented Oct. 17, 1916.

Application filed December 3, 1914. Serial No. 875,366.

To all whom it may concern:

Be it known that I, WALTER D. STAFFORD, a citizen of the United States, residing at Pittsfield, in the county of Berkshire and State of Massachusetts, have invented certain new and useful Improvements in Attachments for Violin-Cases, of which the following is a specification.

This invention relates to an improved form of auxiliary support or carrier for violin cases and other similar objects adapted to be carried under the arm, and comprises a supporting portion in the form of an adjustable arm or bracket arranged lateral to the case, and means for securing the supporting portion in preferably detachable relation on the case.

The practice among violinists of carrying their incased instruments under the arm is very generally observed for convenience and on account of the resulting freedom of the hands for other uses, but it is objectionable by reason of the increased hazard of slipping from the grasp where there is no positive support.

My invention is designed to insure the convenience of this practice and to obviate the hazard stated.

Referring to the accompanying drawings, wherein is shown a preferred form of embodiment of the invention, Figure 1 is a sectional side view of the device operatively mounted upon the cover of a violin case, portions of the case being cut away; Fig. 2, a cross-sectional view of the same on the line *a—a* of Fig. 1; Fig. 3, a similar view on the line *b—b* of Fig. 1, a portion of the arm or bracket being cut away; Fig. 4, a view similar to Fig. 3, showing a full front end view; Fig. 5, a top plan view of the device, portions of the securing strap being cut away; and Figs. 6 and 7, perspective views of the device as it appears operatively mounted upon a violin case and adjusted for actual use.

As shown, the supporting portion of the device comprises an adjustable arm or bracket 1 of spring metal arranged to assume an elevated position at a convenient point on the cover of the violin case 2 and provided at its lower end with a hinge or joint 3, whereby it may be placed in a recumbent position (see dotted lines, Fig. 1) on the case when not in use. The bracket is preferably bowed lengthwise to conform to the arm of the carrier on which it rests to

prevent downward displacement of the violin case, the lower end of the bracket being formed or provided with a spring offset 4, which is preferably raised out of the body 60 of the bracket and arranged to engage the hinge butt 5 for opposing downward movement of the bracket when elevated.

The securing portion of my device comprises a flexible strap 6, preferably constructed of woven fabric or leather, extending across the case cover 2 and provided at each end with a suitable hook plate 7 for detachable connection at opposite points on the case with the lower edges of the cover. 70 Said strap is drawn through a suitable longitudinal slot 8 provided in a rotary shaft 9 which is mounted on upright apertured lugs 10, 10, provided on a base plate 11 arranged on the case cover 2 forward of the bracket 1. 75

The shaft 9 is provided with a head 12 and is rotated for tightening and releasing the strap 6 preferably by means of a removable pin or lever 13 adapted to be inserted in radial openings 14, 14, etc., provided in said head 12, forward or rearward displacement of said shaft on the lugs 10 being opposed by the head 12 at one end and by a washer 15 secured on the opposite end of the shaft by a terminal screw 16. 85

A suitable covering or casing constructed of stamped metal and comprising a top 17, side portions 18, 18, and end portions 19, 19, is shown for inclosing the shaft and attached in any suitable manner to the base 90 plate 11, the end portions 19, 19, being suitably cut away centrally to receive the ends of the shaft 9 which project through said covering.

To secure the shaft 9 in a given position upon tightening the strap 6, I provide a pawl 20 (see Figs. 1, 3 and 4) projecting through a suitable slot 21 provided in the top 17 of the shaft casing and extending downward on one side of the head 12 of the shaft, transversely under the same and upward on the opposite side to a point near the top 17 of said casing, the body portions of the head 12 of the shaft being suitably cut away centrally to allow the pawl 20 to be swung forward free of the rear portion of the head when it is desired to release the shaft for rotation, said rear portion of the head being provided with a square formation to form faces for engagement with the 100 vertical portions of the pawl when secured thereby in locked position, said pawl being 105 110

preferably freely seated in a transversely arranged retaining notch 22 provided in the base plate 11. As shown, the securing strap 6 is arranged to be drawn under the base plate 11, the body-portion of which is offset or bridged centrally (see 23, Figs. 1 and 5) for the free movement of the strap thereunder.

The operation of my device will be readily understood from the foregoing description, taken in connection with the accompanying drawings. When it is desired to adjust the device to the violin case or other object, the pawl 20 is manipulated into a forward position, as shown in full lines in Fig. 1, the shaft 9, being thereupon rotated in the manner above described until the strap 6 assumes a taut, firm position, when the pawl 20 is thrown rearward into the position shown in dotted lines in Fig. 1, so that the faces on opposite sides of the squared portion of the head 12 may engage the vertical portions of the pawl 20. In this position the shaft 9 is secured against rotation and the device retained in rigid position on the violin case.

I claim—

1. In a device of the class described, the combination of a support, an arm pivoted at one end to the support and having a free end for elevation to an upright position over the support, means for limiting the pivotal movement of the arm, means, including a flexible member, for detachably securing the

arm and support to a separate support, and means for regulating the tension exerted on said securing means.

2. A device of the class described, comprising a support, an arm movably secured at one end to the support and having a free opposite end adapted to be elevated at an angle to the support, a flexible securing member transversely arranged on the support and extending beyond the support on opposite sides thereof, means provided at each end of the securing member for attachment to a separate support, and adjustable means for exerting tension on said strap.

3. A device of the class described, comprising a plate, an arm hinged at one end to the plate and arranged to swing at its opposite end into an upright position, a strap arranged transversely across the plate, a revoluble shaft mounted on the plate and arranged to impinge on the strap at its middle, the rotation of the shaft being adapted to regulate the tension on the strap, and a pawl for controlling the movements of the shaft.

In testimony whereof I hereto affix my signature in presence of two witnesses.

WALTER D. STAFFORD.
